UNITED STATES PATENT OFFICE

JAMES G. WITTE, OF KEOKUK, IOWA, ASSIGNOR OF ONE-HALF TO IOWA FIBER BOX COMPANY, OF KEOKUK, IOWA, A CORPORATION OF DELAWARE, AND ONE-HALF TO SOUTH WEST BOX COMPANY, OF SAND SPRINGS, OKLAHOMA, A CORPORATION OF DELAWARE

SHIPPING CONTAINER

Application filed April 18, 1929. Serial No. 356,070.

This invention relates to shipping containers, and among other objects, aims to provide an economical, light, strong and durable shipping container having insulating qualities, so that it is suitable for expressing ice cream cans and the like, and which may be initially shipped knocked-down and flat so as to take up a minimum space in the freight car, and may also be re-used several times.

10 The best material known to me for making shipping containers satisfying the above and other well known requirements is corrugated fiber board, preferably of double thickness, such as is now widely used in making 15 shipping containers for groceries, etc. However, some of the advantages of the invention may be realized by employing other materials.

In the accompanying drawings,

20 Fig. 1 is a vertical section of a shipping container made of double thickness corrugated board, with the top shown open;

Fig. 2 is a horizontal cross section through 25 the same, showing an ice cream can within the container;

Fig. 3 is an enlarged section showing a fragment of one of the walls of the container, showing how the corrugations extend at right angles;

30 Fig. 4 is a plan view of the inside or lining member, shown flat as for shipment, part being broken away;

Fig. 5 is a section on line 5—5 of Fig. 4;

Fig. 6 is a plan view of the outside member of the container, shown flat;

Fig. 7 is a perspective view of the part which fits over the lid of the can; and

40 Fig. 8 is a perspective view of the cushioning and spacing member which fits between the part of Fig. 7 and the foldable flaps which close the top of the container.

Referring particularly to the drawings, there is shown a shipping container which has its three inside dimensions such that it fits snugly over an ice cream can. This container is made of six parts, viz., a collapsible body (shown in Fig. 6), two inside lining and reinforcement members, each similar to the one of Figs. 4 and 5, and three spacing members (Figs. 7 and 8), which are placed

over the ends of the can as indicated in Fig. 1.

The main body is formed from a single sheet 10 of corrugated board of double thickness, folded in three places to make a rectangular body, with four integral end flaps 11, 12 at the top and bottom, respectively. To facilitate assembly with minimum trouble, the two ends of sheet 10 are united, preferably by a flexible hinge 13 (Fig. 6) of gummed cloth, so that while the body may be shipped flat, and hence stacked in tiers in the freight cars, it may also be opened to form a rectangular casing or box, with end flaps ready for folding in along the crease lines 14, thus closing the top and bottom of the casing.

When the bottom is closed, a rectangular reinforcing member 12a (made of two thicknesses of double corrugated board) is thrust into position, as shown in Fig. 1, thus adding greatly to the strength and rigidity of the container and improving its insulating quality.

After folding and securing the lower flaps 12, the casing is greatly reinforced and made a far better insulator by two liners, each of which is like the liner shown flattened out (as for shipment) in Fig. 4, the only difference being that one liner fits inside the other, and is appropriately dimensioned and creased to permit this. The liner 15 (Figs. 4 and 5) is of double corrugated board, with the corrugations running vertically, or longitudinally of the box or casing, while the inside liner 16, also of double corrugated board, has its corrugations running transversely, as shown in Figs. 1 and 2. However, the arrangement may be different, the aim being to have the corrugations of the liners extending at right angles to each other primarily for maximum strength.

The box as so far described is now ready for the ice cream can, which, as shown in Fig. 2, fits snugly inside of the box and reinforces the same, the four inside surfaces of the box being in tangential contact with the metallic can. Thus collapsing of the box with the can inside is made practically impossible, the box being in fact stronger than one made of wood in its resistance to damage from handling.

To close the top and prevent any longitudinal movement of the ice cream can, a pair of spacing and cushioning members 17, 18 are used. The first of these is shown in Fig. 5 7 and is square, flat and made of two double corrugated boards glued or otherwise secured together, with the corrugations of the two pieces extending at right angles, as clearly shown. To receive the lid handle of the ice 10 cream can, the member 17 has a central slot 19. The thickness of member 17 exceeds the amount of protrusion of the handle of the lid above the lid itself, so that the handle is completely surrounded by the member 17 and 15 does not cause any bulging at the top of the box when the latter is completely closed for shipment.

Over the reinforcing and spacing member 17, the member 18 is laid, as shown in Fig. 1. 20 This last may be double corrugated board, as shown, and lies directly below the four top flaps 11 when folded in. The parts are so dimensioned that it is necessary to press the two spacing members 17, 18 firmly in place, 25 and close the flaps with some force, thus obviating any movement of the can or loosening of its lid, with consequent injury to the ice cream inside.

The top flaps 11 are secured in any desired 30 way, as by a glued strip 20 (Fig. 1) or by a few staples (not shown). It will be clear that while I have referred to the flaps 11 as the top flaps, the box 10 has no top or bottom, and the shipper may start from either end, 35 when assembling the container.

When the container with the can therein is received by the retailer, the top is opened by cutting the strip 20, and folding back flaps 11, and the reinforcement 18 is lifted 40 out by hooking a finger through a hole 21 (Fig. 8) near one corner (so as not to be aligned with slot 19). Then reinforcement 17 is removed, and the top of the can is exposed. The can may be removed and set in a cool 45 place, or it may be left in the shipping container if its contents are to be dispensed within a short time. Almost invariably the container will be received in such good condition that it can be shipped back with the 50 empty can in it, thus facilitating return of the empty cans, and eliminating the nuisance of flies in hot weather and the soiling of hands and clothes from the dirty cans.

55 The described shipping container is remarkable alike for its strength and for its insulating quality. The bottom, as shown in Fig. 1, consists of four thicknesses of double board, the four sides are of three thicknesses 60 of double board, and the top has three thicknesses of double board overlaid by two thicknesses from the four folded flaps 11, or a total of five thicknesses of double board everywhere except above slot 19, and three thicknesses 65 above said slot. The offsetting of per-

foration 21 relative to slot 19 prevents air currents from reaching the top of the can.

Another feature is that the six parts which are assembled to make the shipping container are all made of the same material, namely, 70 double corrugated board. This makes for economy of manufacture. Furthermore, the criss-crossing of the corrugated board not only enhances the strength, but prevents some circulation of air inside the box which 75 would otherwise take place.

Other advantages of the box are its lightness, its strength, its immunity from injury arising from handling during shipment, its thermal insulating efficiency, and the fact that 80 it cannot be assembled incorrectly.

Finally, the fact that all six parts of the box may be stacked in tiers because of their flatness, leads to great economies in shipping the containers from the factory making them, 85 because almost every inch of a freight car may be filled with the box parts, with virtually no dead space. If the box were not collapsible, a great deal of space would be 90 lost.

Obviously, the present invention is not restricted to the particular embodiment thereof herein shown and described.

What I claim is:—

1. A shipping container comprising, in 95 combination, an outside casing of corrugated fiber board of double thickness creased so as to be collapsible to be shipped flat and which may be expanded to form a rectangular body; foldable flaps integral with said 100 casing and completely closing the two ends thereof; a corrugated fiber board liner which may be flattened out and which is creased to be folded and received within the rectangular casing and of such dimensions as to contact on all sides with the body which is to be 105 shipped in the container; a second corrugated fiber board liner enclosing the first and interposed between and in contact with both the casing and the first liner; said second liner 110 being creased so as to be capable of shipment in the flat and also foldable to fit in the casing; the inner liner having its corrugations extending transversely of the box and being 115 smooth on its interior face; and means for closing the end flaps of the body.

2. A shipping container composed principally of corrugated fiber board, comprising, in combination, an outside casing or body which is collapsible to be shipped flat and which may be expanded to form a rectangular body; foldable flaps integral with said 120 casing and completely closing the two ends thereof; a liner which may be flattened out and which is creased to be received within the rectangular casing and of such dimensions as to contact on all sides with the body which is to be shipped in the container; reinforcing, insulating and spacing members 125 both at the top and at the bottom of the cas- 130

ing, inside of the flaps when folded, each member being of two thicknesses of double board glued together; the reinforcing member at the top having a central slot cut to receive a handle or the like and having a thickness at least equal to the height of the handle so that the latter does not project above the reinforcing member; another reinforcing, insulating and spacing member fitting within the liner directly above said slotted member to close said slot and cover said handle; and means for closing the end flaps of the body.

5 In testimony that I claim the foregoing
10 as my own I have hereunto affixed my signature.

JAMES G. WITTE.
